UNITED STATES PATENT OFFICE.

HARLEIGH PARKHURST, OF WALPOLE, NEW HAMPSHIRE, ASSIGNOR TO AGNES BURTON, OF MINNEAPOLIS, MINNESOTA.

AIR-COMPRESSOR.

1,201,616.

Specification of Letters Patent. Patented Oct. 17, 1916.

Application filed November 25, 1913. Serial No. 803,014.

To all whom it may concern:

Be it known that I, HARLEIGH PARKHURST, a citizen of the United States, and resident of Walpole, in the county of Cheshire and State of New Hampshire, have invented new and useful Improvements in Air-Compressors, of which the following is a specification.

This invention relates to air compressors, and particularly portable air compressors, and its object is to provide a novel and improved air compressor of simple and compact construction, capable of great efficiency and high speed.

With this invention the crank-case is utilized for the compression of air during the stroke of the piston which corresponds to the suction stroke in ordinary single acting air compressors or pumps, and the air thus compressed is introduced into the cylinder at about the time, or just before, the piston begins its stroke which is commonly termed the compression stroke, thereby increasing the volumetric efficiency of the compressor. As the stroke of the piston corresponding to the usual suction stroke, not only sucks air into the cylinder, but also compresses air in the crank-case for the purpose aforesaid, it may be termed the crank-case compression stroke; while the stroke corresponding to the usual compression stroke may be termed the main compression stroke.

In the accompanying drawings, which illustrate one embodiment of the invention, Figure 1 is a vertical central section of an air compressor containing my invention;—Figs. 2, 3, 4, 5 and 6 represent diagrammatically successive positions of the parts through one cycle of operation of the compressor shown in Fig. 1; Fig. 7 is a sectional view on line 7—7 of Fig. 1; Fig. 8 is a vertical, central section showing a form of check valve appropriate for said compressor; Figs. 9 and 10 are plan views of the valve members shown in Fig. 8; and Fig. 11 is a section on line 11—11 of Fig. 8.

A represents a cylinder, B a piston working within said cylinder, and C a crank-case directly connected to one end of the cylinder and forming part of the air passage, through which air passes and in which air is com-

pressed, on its way to the discharge or compression end of the cylinder, as hereinafter described. The crank shaft *c* extends 55 through the crank-case and may be driven by a pulley or any suitable means (not shown). The crank shaft *c* carries the crank *c'*, which reciprocates the piston B by link or connecting rod *c''*, pivoted at one end to 60 the crank and at the other end to the piston. D represents a sleeve valve fitted to slide within cylinder A between the piston B and the walls of the cylinder. Motion is imparted to sleeve valve D by connecting rod 65 *d* which is pivoted at one end to a pin or stud *d'* on the sleeve, and having at the other end a strap *d''* engaging an eccentric (or crank) *d'* which is fast to and actuated by crank shaft *c*. The eccentric *d'* and crank *c'* are angularly arranged with relation to each other, so that the strokes of the piston B and the sleeve valve D, instead of taking place in unison, are differently timed. In the embodiment of the invention illustrated in the drawings, the eccentric *d'* and crank *c'* are arranged at an angle of about 70 90°, and the piston B is therefore timed to make its stroke a little in advance of the sleeve valve D. It will be understood that 75 this particular angular relation, and relative timing of the parts, are not essential.

An air inlet passage *e*, leading from the supply port *f*, communicates with the interior of crank-case C, through the lower 85 part of the cylinder at the crank-case compression side of the piston B; and another inlet passage *g*, opening from supply port *f*, communicates with the other end of the cylinder to admit air to the cylinder at the 90 main compression side of the piston. The crank-case outlet passage *h* connects the crank-case C with the discharge end of cylinder A at a point just beyond the head of the piston B when the piston is at the 95 end of its crank case compression stroke.

The valve D is provided with ports *i*, *j* and *k*, which coöperate respectively with passages *e*, *h* and *g*. Said ports are controlled by the relative movements between 100 the sleeve D, the cylindrical walls *b* of the piston B, and the cylinder A, as hereinafter described.

E represents the cylinder head having out-

let ports m , controlled by outwardly opening check valves, and p is the main discharge port of the compressor.

The relative location and arrangement of the ports in sleeve valve D, the air passages through the cylinder and crank-case, and the cylindrical walls b of the piston, can best be described and understood by following the action of the parts during one complete cycle in the operation of the compressor. In Fig. 1 the parts are shown in the positions they occupy at the end of the operative or main compression stroke of the piston. In this position, considering the rotation of the 10 crank shaft c to be in a clockwise direction as viewed in the drawings, the eccentric d will have made about three-fourths of a revolution, and the sleeve valve D will be about half way between its two extreme positions, 15 while the crank c' will be at its center, and the piston will be at its extreme position in the compression or discharge direction. The port i controlling the crank-case inlet passage e will then be open to passage e , but 20 about to close upon the next upward movement of the sleeve D; the port j will register with the crank-case outlet passage h but be closed by the wall b of the piston; and the port k will be out of register with cylinder 25 inlet passage g and therefore closed. When the crank c' is turned through the first part of its rotation to the position substantially as shown in Fig. 2, the sleeve D will be moved upward, thereby closing inlet passage 30 e to the crank-case, maintaining crank-case outlet passage h closed (the port j being covered by both the cylinder and piston), and opening cylinder inlet passage g through port k to the main compression side of the 35 piston. At the same time piston B will have started to move downward, compressing the air within the crank-case, and drawing air inward into the cylinder through port K.

Fig. 3 shows the position of the parts when the crank c' has been turned to a position a little short of the end of the crank-case compression stroke. Both the sleeve D and piston B will then be moving downward, and port i will be approaching passage e . The piston will, however, have moved in advance of the downward stroke of the sleeve so as to cover port i and keep passage e closed, allowing the compression of air within the crank-case to continue. 45 The port K admitting air on the main compression side of the piston is about to close, by reason of the downward movement of the sleeve D, and the port j is still closed but is about to open. At this stage the 50 volume of air admitted to the crank-case when the piston was in the position shown in Fig. 1, is compressed within the crank-case, and the cylinder on the other side of the piston is filled with air at substantially atmospheric pressure. When the crank c' reaches the end of its crank-case compression stroke, as shown in Fig. 4, the sleeve D will be approximately half way on its downward movement, and port j will be uncovered by piston B and will register with crank-case outlet passage h , permitting the air compressed within the crank-case C to pass under compression into the cylinder at the discharge side of the piston thereby increasing the volume of air in the cylinder, 70 port i remaining closed by piston B. In this position the main cylinder inlet passage g will be closed by reason of the downward movement of port K. Upon the next movement, therefore, when the piston starts its 75 main compression stroke, the cylinder will have received a volume of air from the crank-case in addition to the air directly drawn in through the main inlet passage g . As the crank c' rotates farther to the position shown in Fig. 5, the sleeve D continues its downward movement cutting off the crank-case outlet passage h , and the piston B starts to move upward and to compress and force the air outward through 80 outlet valve ports m and main discharge port p , the continued downward movement of sleeve D maintaining the main cylinder inlet passage g closed. As the pressure within the crank-case will already be somewhat above the atmosphere, it is not necessary that the crank-case inlet passage e should open at once, as the air will expand sufficiently during the first part of the upward stroke without further supply, and at 85 the same time assist said stroke. In the position shown in Fig. 5 the port i is about to be uncovered by the operative or upward stroke of the piston. When crank c' has made about one-sixth or one-fifth of its upward movement, the piston B will uncover port i and open inlet passage e to admit air to the crank-case through port i ; and both 90 ports j and K will remain closed, while port i will remain open, as shown in Fig. 6, until the piston approaches the end of its main compression stroke. At the completion of the rotation of crank c' the parts will be 95 brought into the position shown in Fig. 1 from which we started, and the cycle will be 100 complete.

It will be understood that the cycle above described could be effected by other means than the sleeve valve above described, and the invention in its broadest aspects is not 105 limited to that particular form of control valve.

With the above described apparatus it will be seen that during the crank-case compression stroke of the piston, air will be admitted at atmospheric pressure at the discharge side of the piston, the crank-case inlet passage e will be closed, and the air previously admitted into the crank-case at the opposite side of the piston will be com- 110

pressed, while the outlet passage h from the crank case to the cylinder will remain closed; that at or about the end of the crank-case compression stroke the main cylinder inlet passage g at the discharge side of the piston will close, and the outlet passage h from the crank-case to the cylinder will open, permitting the compressed air to enter the cylinder; and that during the first 10 part of the main compression stroke of the piston said passage h will close, passage g will remain closed, and the passage e will open to supply air to the crank-case, ready for the next crank-case compression stroke.

15 By thus supplementing the supply of air normally drawn into the cylinder on the main compression side of the piston, with additional air forced into the cylinder under the crank-case compression, a higher volumetric efficiency is insured than has heretofore been attainable.

The crank-case is air tight and forms in effect an auxiliary compression chamber by which the volumetric efficiency of the main 25 compression chamber in the cylinder is augmented by the air supplied from the auxiliary compression chamber through the connecting passage h .

Inasmuch as the eccentric d^2 , eccentric 30 strap d' , and connecting rod d are offset from the axis of the sleeve valve D , there is a tendency to rotate the sleeve except when the eccentric strap is in its two extreme positions. To overcome this a boss or projection d^3 is provided on the outside of sleeve 35 D , which works in a guideway or channel n formed in the inner walls of the casing A .

Referring now to the check valve illustrated in Figs. 7 to 10, the valve ports m are 40 arranged in two concentric circles in the cylinder head E . The outer row of ports is controlled by the annular valve q which covers the entire row, and the inner row of ports is controlled by a similar, but smaller 45 annular valve r . The cylinder head E is provided with an annular flange or rim t , which centers and guides the valve ring q , and a central stud or shaft t' which centers and guides the inner ring r . Two concentric 50 coil springs, s and s' press valves q and r , respectively, toward their seats. Said springs bear at their upper ends against a disk or frame o , which is adjustably mounted on shaft t' . By adjusting the screw n 55 which is threaded through the outer wall E' of the cylinder head, and bears against disk o on the side opposite the springs s and s' , the tension of said springs may be varied uniformly and simultaneously.

60 The valve q is provided with a series of apertures located at the inner side of the valve ports m , and consisting, as herein shown, of recesses q' formed in the inner periphery of the valve when the valve is 65 lifted. When the valve is lifted from its

seat by the compressed air, the escape of air past the valve is permitted not only above the outer periphery of the valve, but also through the recesses q' at the inside of the row of valve ports. By thus increasing the 70 area of the escape passage, the distance which the valve must be lifted from its seat is decreased, the action of the valve is quicker, and the objectionable pounding of the valve, which often occurs when the valve 75 has to lift far enough to permit the escape of air wholly past the outer periphery, is prevented. The inner valve r is similarly provided with a row of apertures r' , which are arranged at the inner side of the ports m 80 controlled by said valve, for the same purpose as the apertures q' . The use of two or more such annular valves increases the area of the escape passage, and decreases the valve lift, thereby still further quickening the action 85 of the valves and reducing their tendency to pound.

I claim:

1. An air compressor comprising a cylinder constituting a main compression chamber, a piston working in said cylinder, an air tight auxiliary compression chamber on the end of said piston opposite the main compression chamber, inlet passages for said chambers, a connecting passage between said main and auxiliary compression chambers, and means to control said passages whereby the air admitted to the main compression chamber through its inlet passage during the auxiliary compression stroke of the piston, will be supplemented in volume by air compressed within the auxiliary compression chamber, which air is admitted to the main compression chamber through said connecting passage. 95

2. An air compressor comprising a cylinder, a piston working therein, a crank to reciprocate said piston, an air tight crank-case connected to said cylinder forming part of an air passage to the cylinder, a main air 100 inlet passage communicating with the cylinder, an air inlet passage communicating with the crank-case, a crank-case outlet passage connecting the crank-case and the cylinder, and means controlling said passages, 105

adapted to open said main inlet passage to the cylinder during the crank-case compression stroke of the piston, also to admit air to the crank-case during the main compression stroke of the piston, also to close said 110 main cylinder inlet passage substantially throughout the main compression stroke of the piston, also to close the crank-case inlet 115 passage substantially throughout the crank-case compression stroke of the piston, where- 120 by the piston will compress the air in the crank-case, also to maintain said crank-case outlet passage closed during both the main compression stroke and the crank-case compression stroke excepting at about the time 125 130

of the reversal of the piston from the crank-case compression stroke to the main compression stroke and momentarily to open said crank-case outlet passage at about said time 5 of reversal of the piston, thereby admitting air compressed in the crank-case to the cylinder.

3. An air compressor comprising a cylinder, a piston working therein, a crank to reciprocate said piston, an air tight crank-case connected to said cylinder forming part of an air passage to the cylinder, a main air inlet passage communicating with the cylinder, an air inlet passage communicating 10 with the crank-case, a crank-case outlet passage connecting the crank-case and the cylinder, and a sleeve valve controlling said passages and fitted to slide in said cylinder between said piston and the walls of the cylinder, adapted to open said main inlet passage to the cylinder during the crank-case compression stroke of the piston, also to admit air to the crank-case during the main compression stroke of the piston, also to 15 close said main cylinder inlet passage substantially throughout the main compression stroke of the piston, also to close the crank-case inlet passage substantially throughout the crank-case compression stroke of the piston, whereby the piston will compress the air in the crank-case, also to maintain 20 said crank-case outlet passage closed during both the main compression stroke and the crank-case compression stroke excepting at 25 about the time of the reversal of the piston from the crank-case compression stroke to the main compression stroke, and momentarily to open said crank-case outlet pas-

sage at about said time of reversal of the piston, thereby admitting air compressed in 40 the crank-case to the cylinder.

4. An air compressor, comprising a cylinder, a piston working therein, a crank shaft and crank to reciprocate said piston, an air tight crank-case connected to said 45 cylinder forming part of an air passage to the cylinder, a sleeve valve fitted to slide in said cylinder between the piston and the walls of the cylinder and actuated by said crank-shaft, a main air inlet passage to said 50 cylinder at the main compression end of the piston, an air inlet passage to the crank-case, and an air outlet passage from the crank-case to the cylinder, said sleeve valve having ports coöperating with said several 55 passages and controlled by the cylinder and piston to open said main inlet passage to the cylinder during the crank-case compression stroke of the piston and to close the same during the main compression stroke of the 60 piston, to close said air inlet passage to the crank-case during said crank-case compression stroke and to open the same during the main compression stroke, and to close said air outlet passage from the crank-case to the cylinder during both strokes and open the 65 same momentarily at about the time of the reversal of the piston from the crank-case compression stroke to the main compression stroke. 70

Signed at Boston, Massachusetts, this 21st day of November, 1913.

HARLEIGH PARKHURST.
